ERNESTO STASSANO, OF TURIN, ITALY.

ELECTRIC FURNACE.

1,157,819.

Specification of Letters Patent.

Patented Oct. 26, 1915.

Application filed August 24, 1914. Serial No. 858,262.

To all whom it may concern:

Be it known that I, ERNESTO STASSANO, residing at Turin, Italy, have invented certain new and useful Improvements in Electric Furnaces, of which the following is a specification.

This invention relates to the mounting of rods for carrying electrodes in electric arc furnaces and has for its object to provide 10 an efficient electrode guide and a thorough cooling of all parts adjacent to the electrode.

On the accompanying drawing is represented, by way of example, one form of the invention, Figure 1 showing in longitudinal 15 section the chamber that incloses the electrode, Fig. 2 is a cross section along the line $\alpha-\alpha$ of Fig. 1, and Fig. 3 is a section along the line $y-y$ of Fig. 1.

As will be seen in the drawing, the chamber, in which is inclosed the electrode and its rod, consists of a cylindrical element 1 adapted to be mounted on the wall of the furnace and with which is connected another element 2 provided at its lower part with 25 extension 3 of rectangular section. The front wall 4 of the chamber thus constituted is of refractory material and is provided with a central hole through which the electrode 5 passes; around the end of cylinder 1 30 encircling wall 4 is arranged an annular chamber 6 through which, by means of conduits 7 and 8, occurs a circulation of water for cooling wall 4.

The casing 2 with a view to its being 35 cooled, has wing members 9 projecting from its wall, and there is at its rear end an annular chamber 10 for the circulation of water. Against this end is applied, by means of a ring 11 of insulating material, 40 the plate 12 provided with a hole suitably coated with insulating material and through which passes rod 13 to which is connected the electrode. This rod carries at its front end a threaded coupling or sleeve 14 serving for 45 the mounting of the electrode and to allow an efficient cooling of the electrode connection it is made hollow and carries within it an insulated tube 15 in the interior of which another tube 16 is mounted, this tube serving 50 to conduct to the end of the tube 15 the circulating water which is discharged at the external end of the rod. The mounting of this rod is such as to exclude all possibility of its bending. At its front end, opposite sleeve 14, it is connected to an insulated bridge piece 17 provided with wheels

18 also insulated with respect to the coupling or sleeve 14 and adapted to travel on two rails mounted on and insulated from the lower end of the extension 3. At the 60 rear extremity of rod 13 is mounted, in insulated manner, the stirrup 20 connected to the carriage 21 which is adapted to slide on rods 22 fixed on the exterior front of the chamber 2 and themselves interconnected by 65 means of the cross piece 23. Carriage 21 is connected by an arm 24 to the rod 25 of a piston movable in cylinder 26 wherein water pressure for imparting the desired movements to the electrode is produced. 70

By reason of the cooling due to the water circulation set up in the interior of rod 13 and in the annular chambers 6 and 10, it is possible to arrange in wall 4, which separates the furnace chamber from that of the 75 electrode, an aperture just large enough for the passage of the electrode, so that the loss of heat is reduced to a minimum and a watertight closure is effected when a pressure or vacuum has been created in the fur- 80 nace chamber.

The front end of the rod carrying the electrode can in consequence of the above described arrangement, be guided in such a way that, while maintaining perfect insulation, the rod itself cannot bend under the weight of the electrode. 85

What I claim as my invention and desire to secure by U. S. Letters Patent is:—

1. Arrangement for mounting the electrodes in electric furnaces comprising a casing adjacent to the smelting chamber, a front wall in said casing provided with a hole for the passage of the electrode, said wall being cooled by circulating water, a rod 90 to which the electrode is connected, supports for the ends of said rod, members carried by said casing on which said supports may slide, and means for causing said rod to travel in order to control the position of 100 the electrode.

2. Arrangement for mounting the electrodes in electric furnaces comprising a casing adapted to be secured to the smelting chamber, a front wall in said casing provided with a hole for the passage of the electrode, said wall being cooled by circulating water, a rod to which the electrode is connected, a support for the rear end of said rod, slides on which said support may 105 run, an insulated stirrup on the front end of the rod, insulated wheels on said stirrup 110

and insulated rails on the bottom of the casing on which said wheels may run, and means for causing said rod to travel in order to control the position of the electrode.

5. Arrangement for mounting the electrodes in electric furnaces, comprising a casing adapted to be secured to the smelting chamber, a front wall in said casing provided with a hole for the passage of the electrode, said wall being cooled by circulating water, a hollow rod to which the electrode is connected, means for establishing a circulation of water in said rod, a support for the rear end of said rod, slides on which said support may run, an insulated stirrup on the front end of the rod, insulated wheels on said stirrup and insulated rails on the bottom of the casing on which the said wheels may run, and means for causing said rod to travel in order to control the position of the electrode.

4. Arrangement for mounting the electrodes in electric furnaces, comprising a

casing adapted to be secured to the smelting chamber, ribs on said casing for cooling purposes, a front wall in said casing provided with a hole for the passage of the electrode, said wall being cooled by circulating water, a hollow rod to which each electrode is connected, means for establishing a circulation of water in said rod, a support for the rear end of said rod, slides on which said support may run, an insulated stirrup on the front end of said rod, insulated wheels on said stirrup and insulated rails on the bottom of the casing on which the said wheels may run, and means for causing said rod to travel in order to control the position of the electrode.

In testimony whereof I affix my signature 40
in presence of two witnesses.

ERNESTO STASSANO.
